GARMENT HANGER

Rose Waldman, Jersey City, N. J.

Application July 18, 1952, Serial No. 299,544

1 Claim. (Cl. 223—89)

This invention relates to new and useful improvements in clothes hangers, garment hangers or coat hangers adapted to hold men's suits.

More particularly, the present invention proposes the construction of an improved unitary hanger having an arched shoulder bar and a horizontal bar spaced from the shoulder bar by a single inclined member to permit a coat, jacket or blouse to be hung on the hanger first as it is taken off and trousers to be hung on the horizontal bar without removing the other garment.

Another object of the present invention proposes forming the hanger with a dependent horizontal bar having a free end and spaced from the shoulder bar so that trousers may be put on the hanger and removed from it without pulling them through the hanger and so that trousers on the horizontal bar will hang fully visible in front of the coat or other garment on the shoulder bar making it unnecessary to open the coat or other garment to see if trousers are on the hanger.

Still further, the present invention proposes constructing the hanger with an inclined member between the shoulder and horizontal bars to extend from a coat, hung on the shoulder bar, between its lapels to dispose the horizontal bar and trousers thereon exteriorly of the coat with the coat bearing against the inclined member and the trousers on the horizontal bar thereby holding the lapels of the coat in smooth condition.

As a further object, the present invention proposes arranging the hanger so that trousers, shorts or other such garments may be hung on the horizontal bar. Skirts or similar garments may be hung or clipped on it or removed easily and conveniently without disturbing or removing the garment hung on the shoulder bar of the hanger.

The present invention further proposes a novel arrangement of hanger structure which is simple, attractive, compact, efficient and durable and which can be economically manufactured and sold at a reasonable cost.

For further comprehension of the invention and of the objects and advantages thereof, reference will be had to the following description and accompanying drawings, and to the appended claim in which the various novel features of the invention are more particularly set forth.

In the accompanying drawings forming a material part of this disclosure:

Fig. 1 is an elevational view of the hanger of the present invention with a man's suit hung on it.

Fig. 2 is an elevational view of the hanger without the suit.

Fig. 3 is a sectional view taken on line 3—3 of Fig. 2.

Fig. 4 is a view similar to Fig. 2, but illustrating a modification of the present invention.

Fig. 5 is a sectional view taken on line 5—5 of Fig. 4.

Fig. 6 is a view similar to Figs. 2 and 4, but illustrating a further modification of the present invention.

2

Fig. 7 is a sectional view taken on line 7—7 of Fig. 6.

Fig. 8 is a sectional view taken on line 8—8 of Fig. 6.

Fig. 9 is a sectional view taken on line 9—9 of Fig. 6.

Fig. 10 is a sectional view taken on line 10—10 of Fig. 4.

The hanger, in accordance with the first form of the invention illustrated in Figs. 1 to 3 inclusive, has an arched upper or shoulder bar 15 curved to fit and complement the shoulders of a coat-type garment such as the coat 16 of the suit shown in Fig. 1. A hook 17, of wire or similar material, is swivelly connected to the upper or shoulder bar at its central portion and projects above the shoulder bar in the conventional manner.

Rigidly connected to one end of the shoulder bar 15 is an inclined S-shaped member 18, the upper end 19 of the member 18 being secured to end 20 of the shoulder bar 15.

The inclined S-shaped member 18 is connected to a lower and horizontal bar 21, the lower end 22 of the member 18 being connected with one end, 23, of the horizontal bar 21. The other end, 24, of the lower or horizontal bar is free and underlies end 20 of the shoulder bar 15 to which the upper end 19 of the inclined member 18 is secured. By this arrangement, the arched shoulder bar 15 has a dependent horizontal bar spaced from it by a single inclined member 18, the shoulder bar 15, member 18 and horizontal bar 21 being in the same vertical plane.

The shoulder bar 15, inclined member 18 and horizontal bar 21 preferably are integral and of homogenous material for a single unitary hanger structure. The material may be wood, metal, plastic or the like. The shoulder bar 15, member 18 and horizontal bar 21 are all T-shaped in cross-section having upper flanges 25, 26 and 27 respectively with lower stems 28, 29 and 30 respectively.

Inclined member 18 projects from the under edge or lower stem 25 of shoulder bar 15, the upper edge or flange 26 of the member 18 projecting at a substantial inclination downwardly from a point near end 20 of the shoulder bar 15. The lower end 22 of the inclined member 18 is curled about to form the horizontal bar 21 which extends in the opposite direction.

By this construction, the coat 16 of the suit shown in Fig. 1 may be placed on the shoulder bar 15 in the usual manner but with the downwardly inclined member 18 extending out of the coat between the lapels and the horizontal bar 21 is disposed outside the coat across the front of the garment. When the hanger is suspended by its hook, the coat will be urged by gravity toward the vertical plane of the hanger and will abut and press against the member 18 and horizontal bar 21 of the hanger. These hanger elements will maintain the lapels of the coat in a smooth condition.

Trousers 31 of the suit may be slid onto the horizontal bar 21 at its free end 24 without disturbing the coat 16 and will be supported externally of the coat on the horizontal bar 21. The trousers 31 extend downwardly in front of the coat pressed against it and this frictional contact retains the trousers on the bar 21 and prevents them from slipping from the bar.

This construction is such that with a coat in position on the hanger and the hanger suspended from the usual bar in a closet or the like, it is possible to hang a pair of trousers over the bar 21 without having to remove the hanger from the closet. Merely swinging the hanger in a direction so that the coat moves away from the side of the horizontal bar 21 leaves a clear space between the

bar and the coat so that trousers can be slipped into position over the free end of bar 21. The hanger may then be released and will be drawn back to its hanging position by the weight of the garments on it, the trousers bearing against the coat to prevent them from falling from the hanger and holding the lapels of the coat in flat, unwrinkled position.

The modified form of the invention shown in Figs. 4 and 5 is characterized by the provision of an arcuate shoulder bar 32 of elliptical cross section having a hook 33 swivelly attached to it, and similar in all other aspects to shoulder bar 15 illustrated in Figs. 1 to 3, inclusive. An inclined S-shaped member 34, round in cross section, connects a horizontal bar 35 to the shoulder bar 32 in the same manner as described above. The simple form of these elements permits the hanger to be made at a minimum cost.

In the modification of the invention illustrated by Figs. 6 and 7, the hanger is constructed and arranged so it may be folded up for packing or to conserve storage space. An arcuate shoulder bar 36 has two ends 37 and 38 and a centrally attached swivel hook 39. An S-shaped inclined member 40 is pivotally connected at its upper end 41 to end 38 of the shoulder bar 36 as by a pin 42. A horizontal bar 43 is pivotally secured to the inclined member 40, the lower end 44 of the member 40 being secured to one end 45, of the horizontal bar 43 by a pivot pin 46. The other end 47 of the horizontal bar is free. An abutment stud 48 on the inclined member 40 near its upper end 41 in the slot 48' on the upper edge of the shoulder bar 36 when the inclined member is hanging down in its operative position shown in the solid lines in Fig. 6.

Horizontal bar 43 has a similar abutment stud 49 adjacent its secured end 45 which rests in slot 49' on the upper surface of the inclined member 40 and holds the horizontal bar 43 horizontal in its operative position. To fold up the hanger in its folded position shown in dot-dash outline in Fig. 6, the lower end 44 of the inclined member is moved toward the shoulder bar pivoting on

the pivot pin 42 and the free end 47 of the horizontal bar is also moved toward the shoulder bar, the horizontal bar pivoting on its pivot pin 46.

It will be noted that horizontal bars 30, 35 and 43 each are inclined upwardly, slightly to assist in retaining the trousers thereon.

While I have illustrated and described the preferred embodiments of my invention, it is to be understood that I do not limit myself to the precise constructions herein disclosed and the right is reserved to all changes and modifications coming within the scope of the invention as defined in the appended claim.

Having thus described my invention, what I claim as new and desire to secure by United States Letters Patent is:

A garment hanger comprising an arcuate shoulder bar, a wire hook centrally attached to the shoulder bar, an S-shaped member having one end pivotally secured to the shoulder bar at one end of said bar with a diagonal downward inclination toward the other end of the bar, a straight bar pivotally secured to the lower end of the inclined S-shaped member, means to hold the S-shaped member in its inclined position and means to hold the straight bar extending substantially horizontally from the lower end of the S-shaped member toward the secured end of the shoulder bar, said means to hold the S-shaped member being a pin fixed to said member to abut the upper edge of the shoulder bar when said member is in its inclined position and said means to hold the straight bar horizontal being an abutment stud fixed to the straight bar at its secured end and adapted to abut a slot formed in the upper edge of the inclined member when the straight bar is horizontally disposed.
